DENTAL CHAIR OR SIMILAR ARTICLE

Ralph J. Motto, Napoleon Novelli, and Vincent M. Novelli, Chicago, Ill.

Application June 22, 1953, Serial No. 25,596

Term of patent 14 years

(Cl. D15—3)

FIG. 1

FIG. 2

FIG. 3

FIG. 4

Figure 1 is a front elevational view of a dental chair showing our new design with the head rest element represented in Figures 3 and 4 omitted for convenience of illustration;

Figure 2 is a side elevational view of the chair as shown in Figure 1; and

Figures 3 and 4 are rear and front perspective views, respectively, thereof.

The dominant features of the design reside in the portions shown in full lines.

We claim:

The ornamental design for a dental chair or similar article, substantially as shown and described.
